J. J. DALY

SHOE

Filed Jan. 22, 1923

FIG. 3.

Inventor:

JOHN J. DALY

by

Deen Dcag.

Atty.

UNITED STATES PATENT OFFICE.

JOHN J. DALY, OF NEWTON CENTER, MASSACHUSETTS.

SHOE.

Application filed January 22, 1923. Serial No. 614,110.

To all whom it may concern:

Be it known that I, JOHN J. DALY, a citizen of the United States, residing at Newton Center, county of Middlesex, Commonwealth of Massachusetts, have invented 5 certain new and useful Improvements in Shoes, of which the following is a specification.

In the shoemaking art, various developments and improvements have been made 10 in shoe structures. The sole, as the important service element of the shoe, is under exacting requirements and exhaustive test. The primary requirement is durability or 15 life and with this is coupled various desirable qualities, such as comfort, protection against moisture, appearance and many others.

My present invention relates to a multiple-soled shoe having an outer sole and 20 an intermediate sole of resilient but wear resisting cushioning material substantially coextensive with and similar in outline to said outer sole and stitched to the upper 25 by a line of stitching independent of the stitching which secures the outer sole to the intermediate sole whereby the outer sole, when worn through, may be readily disconnected from the intermediate sole and the latter exposed as a new, complete and 30 unworn surface for direct contact with the ground.

I have discovered that by using an intermediate sole of resilient but wear resisting 35 cushioning material and stitching said sole to the upper independently of the stitching which secured the outer sole to the intermediate sole, the outer sole will be uniformly yieldably supported thereon throughout its extent so that the wear on said outer sole will be distributed over a large area instead of being concentrated in a restricted zone of bearing, and hence the life of the outer sole will be considerably increased. 40 Moreover the outer sole, when worn through, may be conveniently severed from the shoe without disturbing the theretofore covered and protected line of stitching which securely attaches the intermediate sole to the upper, and said intermediate sole exposed 45 to the ground as a new, complete and unworn wear surface.

The advantages of my invention are three-fold in that by it I am able to avail myself, (1) of the full normal life of the outer sole, plus (2) an added increment repre-

senting the increased wearability imparted to the outer sole by the uniform wear distributive effect of the resilient intermediate sole, and (3) the full normal life of the intermediate sole as a new, complete and unworn wear surface when exposed to the ground, all in a construction in which the individual soles are so attached to the upper that the outer sole, when worn through, 60 may be disconnected from the intermediate sole with the minimum of inconvenience and the latter exposed to the ground as a full wear surface.

Tests of shoes made in accordance with 70 my invention show an actual increase of from two to three months in the life of the outer sole, even where a very light outer sole is used, over a double-soled shoe in which the intermediate sole is not designed 75 to have any cushioning and wear distributing effect upon the outer sole.

For the purposes of this application, I shall show and discuss my invention in its adaptation to a welt shoe. It will be understood, however, that such treatment is purely 80 illustrative and in no way limiting. The construction of my shoe is described and illustrated in the accompanying specification and drawings and the characteristic features of novelty are particularly pointed out 85 in the appended claims. Throughout the specification and drawings like reference characters are correspondingly employed, and in the drawings: 90

Figs. 1 and 2 are side and bottom views of a shoe in accordance with my invention.

Fig. 3 is a top plan view at the toe particularly showing the independent lines of stitching which attach the outer and intermediate soles to the upper. 95

Fig. 4 is a section on the line 4-4 of Fig. 3, and

Figs. 5 and 6 are fragmentary detail views showing a modification. 100

I have indicated at A the upper and at W the welt of a double soled welt shoe in accordance with my invention.

Stitched to the welt W at S² is an intermediate sole X of resilient but wear resisting cushioning material. The sole X conforms in outline to and is substantially coextensive with the outer sole Y which is stitched at S¹ to the intermediate sole X and welt W by a line of stitching independent 105 of the stitching S² which secures the intermediate sole X to said welt. (See Fig. 4.) 110

In Figs. 1 and 2 the outer sole Y is shown as terminating at the breast B of the heel H. In Figs. 5 and 6 said sole is skived and extended as a point or tip Y², preferably 5 triangular in form, which is inset centrally of the heel and tacked thereto as at T so that when the outer sole is removed no interstice or crack appears between the heel and seat. If desired, however, the sole Y 10 may be full length.

By using an intermediate sole X of resilient but wear resisting cushioning material, the outer sole Y is uniformly yieldably supported thereon throughout its entire 15 extent. This insures that the wear on the outer sole will be distributed over a relatively large area instead of being concentrated in a restricted zone of bearing, thereby diminishing the wear on any one portion 20 of the outer sole. By thus diminishing the wear uniformly throughout the extent of the outer sole, the life of the outer sole is not only considerably increased but the liability of the intermediate sole becoming 25 worn in some particular zone of bearing is prevented.

When the outer sole is worn through, it may be readily disconnected from the intermediate sole by severing the stitches S' and 30 the intermediate sole exposed as a new, complete and unworn wear surface for direct contact with the ground, said sole itself being securely attached to the welt by its own independent stitching S².

I thus secure the full normal life of the outer sole plus the increased wear imparted thereto by the wear distributive effect of the resilient intermediate sole, and when 35 said outer sole is worn through and removed I have a complete, new and unworn intermediate sole which itself is securely attached to the welt by a line of stitching which has been theretofore covered and protected by the outer sole.

Moreover, the combined moisture excluding and cushioning effect of the resilient intermediate sole effectually waterproofs the shoe and makes it more comfortable to the foot, without, however, detracting in any 40 way from the characteristic neat appearance of the shoe as an article of footwear.

In practice, the welt W is preferably made of slightly greater width than usual in order to allow ample room for the double 45 row of stitching S', S², and this stitching compressibly confines the resilient intermediate sole C so as to secure the maximum cushioning effect.

My invention is capable of adaptation to 50 various types of shoes, and of various modifications in details of structure, all of which

may be resorted to without departing from the underlying concept, if within the limits of the appended claims.

What I therefore claim and desire to secure by Letters Patent is:—

1. In a shoe, an upper structure including an upper and an insole, an intermediate sole of resilient but wear resisting cushioning material underlying and secured to 70 said upper structure, and an outer sole substantially coextensive with and conforming in outline to said intermediate sole and stitched to said intermediate sole and the upper by a line of stitching independent of the means which secure said intermediate sole to the upper whereby the outer sole, when worn through, may be readily disconnected from the intermediate sole and the latter exposed as a new, complete and unworn 75 wear surface for direct contact with the ground.

2. A double soled welt shoe comprising an upper, a welt fastened thereto, an intermediate sole of resilient but wear resisting cushioning material underlying and stitched to said welt, and an outer sole substantially coextensive with and conforming in outline to said intermediate sole and stitched thereto and to the welt by a line of stitching independent of the stitching which fastens said intermediate sole to the welt whereby the outer sole, when worn through may be readily disconnected from the intermediate sole and the latter exposed as a new, complete 90 and unworn wear surface for direct contact with the ground.

3. A double soled welt shoe comprising an upper, a welt fastened thereto, an intermediate sole of resilient but wear resisting cushioning material underlying and stitched to said welt, and an outer sole covering and protecting the stitching which attaches the intermediate sole to the welt and itself stitched through said intermediate sole to 100 the welt by a line of stitching independent of and outside the stitching which fastens said intermediate sole to the welt whereby the outer sole, when worn through, may be readily disconnected from the intermediate sole 105 and the intermediate sole exposed as a new, complete and unworn wear surface for direct contact with the ground.

In testimony whereof I affix my signature in presence of two witnesses.

JOHN J. DALY.
